FLOWER POT HOLDING-TRAY

Bruce Beh, 1150 Broadway,
Huntington, N.Y. 10001

Filed Jan. 30, 1975, Ser. No. 545,300

Term of patent 14 years

Int. Cl. D9—03; D11—02

U.S. Cl. D11—156

FIG. 1.

FIG. 2.

FIG. 3.

FIG. 1 is a top front perspective of a flower pot holding tray showing my new design;

FIG. 2 is a bottom perspective thereof; and

FIG. 3 is a top plan view thereof.

I claim:

The ornamental design for a flower pot holding-tray, substantially as shown and described.
